UNITED STATES PATENT OFFICE.

WILLIAM F. NIEMEYER, OF BROOKLYN, NEW YORK, ASSIGNOR OF ONE-HALF TO
THOMAS J. SHEARER, OF BROOKLYN, NEW YORK.

GAME APPARATUS.

Application filed March 17, 1923. Serial No. 625,726.

To all whom it may concern:

Be it known that I, WILLIAM F. NIEMEYER, a citizen of the United States, residing in the borough of Brooklyn, county of 5 Kings, city and State of New York, have invented an Improvement in Game Apparatus, of which the following is a specification.

This invention relates to a game apparatus, and more particularly to an apparatus for playing baseball. I am aware that heretofore various devices have been designed for playing baseball and similar games, but in all instances of the same which have been 10 brought to my attention the manner in which the game is played and won or lost depends entirely upon chance and not in any degree whatsoever upon the skill of the players. For example, this type of game 15 has customarily been played by spinning a wheel or pin or throwing dice or by a combination of both so that the element of chance is the controlling one in playing the game. Furthermore, in games of this 20 type, which have heretofore come to my attention, while being used by different teams or groups in playing the game one team is active while the other is inactive, and this naturally has a tendency to lessen 25 the interest in playing the game; whereas, in the use of my proposed game apparatus both teams or sides are actively engaged in play as is the case in playing an actual game of baseball, so that the rules covering the 30 real game may be utilized and plays made to represent the actual plays in a real game of baseball.

In carrying out the invention the apparatus preferably comprises a playing board having a baseball diamond marked thereon, together with a plurality of pegs and pockets which are utilized in playing the game to represent the players in certain positions and certain plays, the game being 45 played by different sides or teams with a ball and cue, as will be hereinafter more particularly described.

In the drawing:

Fig. 1 is a plan of a game apparatus made 50 in accordance with my invention, and

Fig. 2 is a section on line 2—2, Fig. 1.

Referring to the drawing, the apparatus made in accordance with this invention preferably comprises a base 10 which may or 55 may not include a suitable stand for sup-

porting the apparatus. In the base 10 there is a playing board 11 upon the upper side of which there is a playing surface indicated at 12. It will be understood that the board member may be made of any suitable 60 material and that the same is also the case with the playing surface. Indicated diagrammatically on the playing surface is a baseball diamond 13. This is made in the usual manner so as to indicate the path between the home plate and the several bases. This includes an alley designated at 14 extending between the pitcher's box and the home plate. The diagram also includes the foul lines 15 and 16 extending from the 70 home plate, as indicated.

Secured in the playing board I employ a plurality of pegs, and also in suitable positions in the playing board there are a plurality of recesses or pockets. The peg 75 17 is designated to represent a batter in position at the bat adjacent the home plate. Behind the batter and at the catcher's station, or in the catcher's position, there are 80 pockets or recesses indicated at 18, 19 and 20. The pocket 18 is employed to designate a strike, the pocket 19 a ball, and the pocket 20 an out.

The bag at first base is indicated by a peg 21, and in a suitable position in the right 85 field behind first and second base and outside of the diamond there is a pocket or recess 22 designated first base pocket. The second base bag is indicated at 23. Behind the second base position there is also a peg 90 24 designated second base, and adjacent the same a pocket 25 designated second base home run. The position of the short stop is indicated by a peg 26 placed in the left 95 field outside of the diamond. The third base bag is indicated by a peg 27, and the third baseman's position is indicated by a peg 28 adjacent which there is also a pocket 29 designated third base home run.

The position of the right fielder is indicated by the peg 30 adjacent which there is a pocket 31 designated safe home run. The position of the left fielder is indicated by a peg 34 adjacent which there is a pocket 35 which is also designated safe home run. 100

The apparatus as constructed is provided with a rail or cushion 36 surrounding the playing surface in much the same manner that the cushion surrounds a billiard or pool table so that the game may be played 110

with a ball 37 made of ivory composition or other material by the use of a cue 38. It will be understood, however, that the game may be equally well played by making the 5 rail of wood or metal and employ a rubber ball instead of a solid ball. It will furthermore be understood that the various pegs as hereinbefore described may be provided with bores or recesses in order to receive 10 figures representing the players if it is desired to use the same; and also that the various pegs may be covered with rubber tubing or other similar material when a solid ball is employed or otherwise 15 protected as may be necessary to prevent the same becoming broken or otherwise injured in the use of the apparatus.

In playing the game with the apparatus hereinbefore described, the players in turn 20 on the team which is in the field play the ball with the cue from the position illustrated in the drawing in which the ball 37 is placed in the pitcher's box so as to represent the pitcher in the actual play of pitch- 25 ing the ball. Likewise the players on the team at the bat take their places in turn at the batter's station or position indicated at 17. Of course the various players may 30 use their judgment as to the play which they would attempt to make in much the same manner that plays are made in the actual game. For example, the player acting as pitcher may endeavor to pitch a strike. In so doing it is necessary to make 35 the ball travel along the alley 14 and to lodge in the pocket indicated 18; or the player acting as pitcher may wish to pitch a ball in which event it is necessary to lodge the ball in the pocket indicated at 19; or 40 in other instances the player acting as pitcher may wish to attempt to put out a player who has reached one of the bases and in so doing it is necessary to cause the ball 37 to lodge in the pocket designated 20. 45 It will be noted that the station of the batter is so placed that the ball must just clear the peg in order to cause it to lodge in the pocket 18, and similarly in shooting the ball from the pitcher's box the ball must be 50 made to just clear the other side of the peg representing the batter to lodge in the pocket indicated at 20. In playing the game should the player not succeed in causing the ball to lodge in either of these pockets of

course it will strike the rail and rebound. 55 It will then be the turn of the next succeeding batter to place the ball at the home plate, and by using the cue to make any play which he may consider advisable; for example he may attempt to make a base hit 60 by causing the ball to lodge in the pocket 22, or he may attempt to make a safe home run by causing the ball to lodge in either of the pockets 31, 33 or 35, it being necessary in some instances to cause the ball to first 65 strike the rail in order to accomplish this. It will then be the next succeeding player's turn to act as pitcher and, for example, he may attempt to put the runner out by shoot- 70 ing the ball into the pocket indicated at 20.

It is thought that the foregoing will serve the purpose of illustrating the manner in which the game may be played, and it will now be obvious that any one of the innumerable plays possible in an actual 75 baseball game may be attempted in the use of this apparatus and that suitable rules may be arranged, based upon the actual rules of playing baseball.

I claim as my invention:

1. A game apparatus comprising a board having a playing surface representing a baseball diamond thereon; a peg fixed in position at the home plate, and recesses or pockets in the playing surface behind the 85 said peg in such positions that a ball struck by a cue in the hands of a player and moved from a position designating the pitcher's box must just clear the said peg on one side to be lodged in one of the said pockets and must just clear the peg on the other side to be lodged in another of the said pockets.

2. A game apparatus comprising a board having a playing surface representing a baseball diamond thereon, a plurality of 95 pegs fixed in the said board to represent the bases and certain players, there being a plurality of recesses or pockets associated with the said pegs whereby when a ball is moved by a cue in the hands of a player 100 from the home plate position it must clear one of the said pegs in order to lodge in a recess or pocket associated therewith to accomplish a predetermined play which depends upon the skill of the player.

Signed by me this 13th day of March, 1928.

WM. F. NIEMEYER.
